RADIATOR GUARD

Earl R. Graves, Riverside, and Stanley C. Powell,
Chicago, Ill., assignors to International Harvester Company, a corporation of New Jersey

Application October 6, 1934, Serial No. 747,166

2 Claims. (Cl. 293—54)

The invention relates to a guard for protecting the cores of radiators as employed in motor vehicles of all kinds. The guard is especially designed for use on tractors where the radiator 5 meets with unusual mechanical abuse. The function of the guard is primarily two-fold; in one instance, it saves the delicate radiator core from damage when struck by objects in the path of travel of the tractor, such as tree branches and 10 the like, and, in another instance, it keeps out material, such as leaves and insects that might clog the core and interfere with the circulation of air therethrough and thus impair its cooling efficiency.

15 Guards for this purpose now generally in use embody a frame carrying a wire mesh screen constructed with separate reinforcement bars. Such structure is too costly and heavy.

The primary object of this invention is to provide a simplified guard for the purposes stated. Another object is to provide a guard eliminating the usual wire screen and substituting therefor a sheet of sheet metal formed with holes and shaped to provide beaded strengthening ribs at 25 spaced intervals therealong.

Other objects will be apparent to those versed in this art as the disclosure is more fully made.

Briefly, such objects may be attained by providing a rectangular piece of sheet metal of the 30 requisite size and pressing the same to form spaced vertical reinforcing beads or ribs. The portion of the sheet metal plate between these ribs is provided with closely arranged openings punched therefrom to permit air to circulate freely therethrough. Frame pieces are then welded to the edges of the plate, said frame pieces being detachably secured to the radiator shell for mounting the guard.

In the drawing showing a practicable example 40 of the improved radiator guard,—

Figure 1 is a front elevational view of the guard mounted on a radiator;

Figure 2 is an end elevational view of the radiator and guard;

45 Figure 3 is an enlarged detail end elevational view of the radiator and guard with a part in section, as taken along the line 3—3 of Figure 1, looking in the direction of the arrows; and,

Figure 4 is a transverse sectional view of the 50 guard per se, taken along the line 4—4 of Figure 1, looking in the direction of the arrows.

The improved guard presently to be described is applied to a radiator shell embodying a top header 5, a bottom header 6, and side frame parts 55 7, all of conventional form. The cooling core

requiring protection is shown at 8. The front face of said core 8 is exposed in the rectangular space formed by the headers 5, 6, and sides 7.

The guard for said core comprises a rectangular sheet of steel and is numbered 9, the same being of the proper size to cover the radiator shell opening. The side edges of said sheet of steel are bent back, as at 10, to strengthen the marginal side edges. At spaced intervals, the sheet has pressed therefrom ribs 11 in beaded or channel form, as appears in Figure 4. These ribs are preferably arranged in parallelism and serve to strengthen the guard against shocks and impacts met in service. Between these ribs 11 the sheet is made foraminous by punching closely arranged 15 holes 12 therein. Thus the sheet itself serves as the screen and it is formed in one piece with the reinforcement ribs 11.

By means of spot welds indicated at 13, angle bar attaching pieces 14 are respectively secured 20 to the top and bottom edges of the plate 9, said pieces 14 being laterally disposed and having ends projected beyond the side edges of the plate 9, as shown in Figure 1. These projected ends are secured by cap screws 15 to the radiator shell sides 25 7, as shown, suitable bosses 16 being provided to make a rigid mounting in properly spaced relation from the radiator shell.

As the screen plate 9 and ribs 11 are in one piece, a sturdy, simplified guard results, which 30 in an effective manner can withstand vibration and abuse. Further, because the attaching bars 14 are welded to the screen plate, the whole guard structure acts effectively in conducting heat from the radiator shell and serves to dissipate it, thus aiding the cooling action.

As the structure described eliminates the usual wire screen and a complete frame, it is capable of production at considerable reduction in cost.

By merely removing the four cap screws 15, the 40 entire guard may be easily and quickly detached from the radiator shell for cleaning. Just as easily the guard may be restored to position on the radiator.

This radiator screen guard is non-vibrating 45 because its strengthening ribs 11 are at spaced intervals and parallel with the vertical rows of holes 12. Further, these holes 12 are aligned with the core openings in the radiator to insure efficient air circulation and proper cooling. Further, 50 leaves and trash are easily wiped from the screen when it gets clogged.

It is the intention to cover all changes and modifications of the illustrative form described and shown which do not depart from the spirit 55

and scope of the invention as hereinafter claimed.

What is claimed is:

- 5 1. A radiator guard comprising a substantial-
ly rectangular flat integral sheet of metal hav-
ing spaced, continuous, vertical, parallel, im-
perforate ribs pressed therefrom extending from
the front face thereof, said sheet having holes
10 formed therein between said ribs, cross angle bars
secured to the upper and lower edges of the sheet
15 with one flange of the bars arranged vertically
against the front face of the sheet whereby the
horizontal flanges of the bars extend rearwardly
to span the upper and lower edges of the sheet to
space the sheet from the radiator to which it is
20 attached, said bars having ends extending later-
ally of the sheet and adapted for securing to the
shell of the radiator, the ribs pressed from the
sheet extending substantially the full height of
the sheet and terminating at their upper and
lower ends short of the upper and lower edges of

the sheet and closely adjacent the respective in-
ner edges of the vertical flanges of the cross angle
bars.

2. A radiator guard comprising a substantial-
ly rectangular flat integral sheet of metal having 5
spaced, continuous, vertical, parallel, imperforate
ribs pressed therefrom extending from the front
face thereof, said ribs stopping at their ends
short of the upper and lower edges of the sheet
10 to leave flat surface portions across the width 10
of the sheet, said sheet being perforated between
the ribs, and cross bars respectively placed flat-
ly at the upper and lower edges of the sheet off
end relative to said ribs and against said flat sur-
face portions, said bars being secured to said sheet 15
and having ends overhanging the side edges of
the sheet and adapted for connection to a radiator
shell.

EARL R. GRAVES.
